FILM FORMING MECHANISM

Edouard M. Kratz, Gary, Ind., assignor by mesne assignments, to Marbo Products Corporation, Chicago, Ill., a corporation of Delaware

Application June 29, 1933, Serial No. 678,308

8 Claims.

(Cl. 18—15)

This invention relates to improvements in film forming apparatus and includes an improved method of forming films on a carrier belt.

More specifically, this invention relates to apparatus for forming uniform, smooth films and applying the same onto a traveling carrier belt.

The formation of smooth and uniform sheets of a transparent nature can be brought about by "setting" a liquid material with another liquid material, forming a film of the materials and casting them onto a traveling belt while they are still plastic. Because of the rapid "setting" action of the liquid ingredients it is necessary that they be mixed together not more than a few minutes before being cast in film form onto a carrier belt. For example, in the formation of thin transparent sheets, composed of casein which has been hardened with formaldehyde or similar hardening agents, the hardening or "setting" action occurs too quickly to permit the mixing of a batch of the active ingredients for casting in films onto the belt. As a result, it is essential that the active ingredients forming the sheets be mixed together to a uniform mixture which is quickly formed into a film and cast onto the carrier belt. If the mixture is allowed to stand more than a few minutes it will set into a viscous jell that cannot be formed into a sheet.

In the application filed by myself and Herman Heckel, Serial 630,406, filed Aug. 25, 1932, there is described a film forming apparatus for manufacturing transparent sheets in which casein and formaldehyde or other hardening agents are mixed together in the proper proportions in a proportioning pump and immediately fed through tubes to a coating roll. A doctor bar is carefully adjusted to a previously determined distance away from the coating roll so as to remove excess material from the roll. This doctor or scraper bar therefore regulates the thickness of the film. After passing under the doctor bar, the casein material on the coating roll contacts a traveling carrier belt and is deposited thereon.

I have now provided improvements in the film forming mechanism described in the copending application Serial No. 630,406.

In accordance with this invention, the reacting ingredients to form the transparent sheets in proper admixed proportions are fed to a rotating coating roll. The thickness of the film on the coating roll is regulated by a reverse coating roll rotating in the same direction as the coating roll and in adjustable spaced relation therefrom. Since the rolls rotate in the same direction a scraping and smoothing action exists between them. As the material picked up by the coating roll passes between the nip of the reverse roll and the coating roll, it is formed into a smooth film which is picked up by the carrier belt. Improved scraping devices are provided to main-

tain the coating roll and the reverse roll in a clean and smooth condition.

It is therefore an object of this invention to provide a film forming mechanism for manufacturing transparent sheet materials.

Another object of this invention is to provide an apparatus for casting films onto a carrier belt in such a manner that an even, smooth and uniform sheet results.

Another object of this invention is to provide a process for forming transparent sheet material from initial ingredients which rapidly react to form a solid mass.

Another object of this invention is to provide film forming apparatus for transparent sheet material manufacture which is capable of accurate adjustment and may be used continuously over long intervals of time without necessity of readjustment.

Other and further objects of this invention will be apparent to those skilled in the art from this specification and the hereinafter described drawings which form part of this description.

On the drawings:

Figure 1 is a side elevational view of the film forming mechanism showing the driving mechanism in dotted lines.

Figure 2 is a broken front elevational view of the film forming apparatus.

Figure 3 is an enlarged sectional view taken substantially along the line III—III of Figure 1.

Figure 4 is an enlarged sectional view taken along the line IV—IV of Figure 2.

As shown on the drawings:

In Figures 1, 2 and 4, the reference numerals 10 indicate vertical supporting means or frame structure for the film forming mechanism. Horizontal supporting arms 11 having flat top surfaces 12 provided with dovetailed grooves 13 are secured to the vertical supports 10.

Bearing carriages 14 for a coating roll 20 are slidable on the surfaces 12 of the supporting arms 11 and have dovetails for fitting into the grooves 13 in the surfaces 12. The carriages 14 carry bearing caps 14a for the roll 20.

The carriages 14 support members 15 which are provided with flat inclined surfaces 16 for receiving bearing carriages 17 for a reverse coating roll 18. The members 15 are bolted onto the carriages 14 by means of bolts 19 (Fig. 2). Carriages 17 support bearing caps 17a for the roll 18.

The bearing carriages 14 for the coating roll 20 are moved along the arms 11 by means of screws 21 rotatably mounted in bosses 22 integral with the supports 11. Hand wheels 23 are provided to manually operate the screws 21.

The bearing carriages 17 for the reverse coating roll 18 moves along the dovetail groove track 16 by means of screws 25 which are rotatably

secured in bosses 26 integral with the supporting structure 15. The screws 25 are actuated by hand wheels 27.

A roll 30, which is preferably rubber covered, is 5 provided for directing a carrier belt 31 against the coating roll 20. The roll 30 is rotatably mounted in bearing supports 32 which are slideable in tracks 33 on the vertical beams 10. Screws 34 are provided for moving the roll 30 10 along the tracks 32. Collars 35 (Fig. 1) are secured to the beams 10 in screw thread relation with the screws 34 so that a rotation of the screws 34 will slide the roll 30 relative to the beams 10. Lock nuts 36 and 37 (Fig. 1) may be 15 provided to hold the bearing supports 32 in adjusted position.

From the above description, it is evident that the rubber covered roll is vertically adjustable along the supporting means 10. The coating roll 20 is horizontally adjusted along the horizontal arm 11 and the reverse coating roll 18 is adjustable on an inclined plane along the supporting member 15. The three rolls may therefore be brought into cooperative relation and adjusted at 25 will to meet whatever changes are necessary. The micrometer adjustment made possible by the use of fine-threaded screws provides minute control of the three rolls at all times.

As shown in Fig. 4, an angle member 39 is rotatable in a U-shaped saddle support 41. A trough plate 40 is secured to the member 39 to scrape against the coating roll 20. End plates 42 are provided to form the ends of the trough. Weights 43 may be adjusted along lever arms 44 35 secured to the member 39 at right angles to the plate 40 for adjusting the pressure of the end of the plate against the coating roll 20.

A plurality of tubes or pipes 45 are secured at their ends in the plate 40 near the lower edge 40 thereof for supplying the film forming material in properly admixed proportion to the trough. A small pond of film forming material 46 (Fig. 4) is therefore maintained in the lower part of the trough formed by the plates 40, 42 and the coating roll 20. This film forming material in the pond is immediately picked up by the roll 20 and formed thereon in a thin film 48 (Fig. 4). The rolls 18 and 20 both rotate in a clockwise direction, (viewed as in Fig. 4), so that their adjacent 50 surfaces move in opposite directions and the excess film forming material is therefore removed and the outside of the film 48 is provided with a smooth surface.

An angle member 49 is rotatably mounted in a 55 U-shaped saddle support 50 for securing a scraper plate 51 in operative position against the reverse coater roll 18. Lever arms 52 are provided for supporting weights 53 which are slidably adjustable thereon. The scraper plate 51 is 60 thus held against the reverse coater roll 18 to remove film forming material therefrom. The pressure of the scraper against the roll may be adjusted by varying the position of the weights 53 along the lever arms 52.

Angle members 60 and 61 rotatably mounted 65 from supports 62 are provided to hold scraper plates 63 and 64. Lever arms 65 and 66 are secured to the angle members 60 and 61 respectively. The lever arms 65 and 66 are connected 70 to spring tensioning means 67 and 68 for adjusting the plates 63 and 64 against the fountain roll 20 to remove any film material which may remain thereon after the film has been transferred to the carrier belt 31. Wing nuts 69 and 70 are provided to regulate the tension of the scraper plates 75

63 and 64 against the roll 20. While two scraper plates 63 and 64 are shown in Fig. 4, it is to be understood that in some instances a single plate 63 may be sufficient as shown in Fig. 1.

As shown in Fig. 3, the reverse coater roll 18 is 5 preferably provided with a central bore or opening 71 to receive heating or cooling fluid from a pipe 72. The roll 18 may thus be maintained at a constant temperature and any expansion or contraction of the roll caused by temperature 10 changes is therefore eliminated. The relative positioning of the rolls 18 and 20 is very important, as the distance between these rolls determines the thickness of the film being formed. These rolls are accurately ground and may be 15 provided with stainless steel jacketed or chromium plated surfaces if desired. A drain line 73 is provided at the other end of the roll 18 as shown in Fig. 2 to remove the fluid introduced through feed pipe 72.

The rolls 18 and 20 are driven in the same direction by separate chain drive means from the same source of power. A chain 80 drives the sprocket gear 81, which is mounted on a shaft 82 in the vertical supporting members 10. The shaft 82 runs across the width of the machine and is provided at its opposite end with a pulley 83 for driving a belt 84, which, in turn, drives a large pulley 85 secured to the shaft of the reverse coating roll 18. An idler gear 86 is preferably 30 mounted on the supporting member 10 adjacent the gear 81 to take up slack in the chain. Likewise, an idler pulley (not shown) may be provided to take up slack in the belt 84 due to stretching or to adjustment of the roll 18.

The coating roll 20 is driven by a chain drive 35 87 which rotates a sprocket gear 88 secured to the shaft 89 of the roll 20. The rolls 18 and 20 are therefore driven in the same direction. However, since their adjacent surfaces travel in opposite directions, the roll 18 is called a reverse coater roll and removes excess film forming material from the fountain roll 20.

The rubber covered roll 30 is driven by the carrier belt 31 which, in turn, is preferably driven by 45 contact with a suction roll (not shown).

The operation of the film forming device may be briefly described as follows. The rolls 18, 20 and 30 are rotated in a clockwise direction (as viewed in Fig. 4), being driven from a suitable 50 power source. Proper contact of the coating roll 20 with the carrier belt 31, as it travels over the rubber roll 30, is made by manual control of the adjusting screws 21. The adjusting screws 25 are set to hold the reverse coater roll 18 in the 55 proper spaced relation from the coating roll 20, so that a sheet of the desired thickness will be formed.

The weights 43 are set to hold the trough member 40 tightly against the coating roll 20. The 60 weights 53 are likewise set to hold the scraper plate 51 tightly against the reverse coater roll 18 and the tensioning devices 67 and 68 are set to hold the scraper plates 63 and 64 against the 65 coating roll 20.

Film forming material, such as casein and formaldehyde, is admixed in the proper proportions by means of a proportioning pump (not shown). The material is then immediately pumped through tubes 45 to the trough 40 in 70 which it forms a pond 46. The rotation of the fountain roll 20 causes a film of the material 48 to be picked up on the periphery of the roll from the pond 46. As the film 48 advances on the roll 20, it passes through the nip of the rolls 75

18 and 20 whereupon it is formed to a uniform thickness and provided with a finished outside surface.

The scraper plate 51 removes any material that is retained on the roll 18 so that the smooth finished peripheral surface of the roll 18 is always presented to the film 48. The roll 18 is preferably chromium plated and highly polished. It may be kept at a uniform, warm temperature by passing hot water through the chamber 71 provided through its interior.

The film 48, after advancing through the nip between the rolls 18 and 20, contacts the carrier belt 31 traveling in a reverse direction thereto. 15 The carrier belt strips the film from the coating roll and as the roll rotates into contact with the scraper plate 64, any of the film forming material which may have had adhered to the roll is removed by the scraper plate. The coating roll is scraped again by a second scraper plate for removing the last traces of foreign material that may have adhered thereto. The surface of the roll next contacts with the pond of film forming material in the trough 40 and picks 20 up a fresh layer of material therefrom.

I am aware that many changes may be made and numerous details of construction may be varied through a wide range without departing from the principles of this invention, and I therefore do not purpose limiting the patent granted hereon otherwise than necessitated by the prior art.

Having now described my invention, what I claim is:

35 1. In a film forming apparatus, in combination, a coating roll, a reverse coating roll, means for driving the reverse coating roll in the same direction as the coating roll, a traveling carrier belt, a rubber covered roll for guiding said carrier belt against said coating roll, means for adjusting said coating roll horizontally, means for adjusting said reverse coating roll along an inclined plane relative to said coating roll, and means for vertically adjusting said rubber covered roll, said means cooperating to provide positive control of formation and thickness of the film.

2. A film forming apparatus for transparent sheet material comprising, in combination with 50 a coating roll, a plate adapted to scrape against said coating roll at an inclined angle thereto, end plates abutting said inclined plate to form a trough enclosure, means for adjusting the scraping action of the plate against the roll, a plurality of feed means for supplying the trough with film forming material whereby a pond of 55 said material is formed against the coating roll and a film of the material is picked up by the coating roll, a cooperative roll in adjustable spaced relation to said coating roll, means for driving said cooperative roll in the same direction as said coating roll whereby excess film forming material is removed from the coating roll as the film thereon passes between the nip 60 of the two rolls and means for transferring the film from the coating roll.

3. Film forming apparatus comprising, in combination, vertical and horizontal supporting members, bearing carriage means slidably on 70 said horizontal supporting members, a coating roll rotatably mounted on said carriage means, bearing supporting means slidably mounted on said first carriage means, a reverse coating roll

rotatably mounted on said bearing supporting means, means for horizontally adjusting said coating roll on said horizontal support and means for adjusting said reverse coating roll along an inclined plane in spaced relation from said coating roll.

4. Film forming apparatus comprising, in combination with supporting means, supporting carriages slidably mounted on said supporting means, bearing means on said slideable carriages, 10 a coating roll rotatably mounted in said bearing means, bearing carriages slidably mounted along inclined planes on said carriage supporting means, a reverse coating roll rotatably mounted in said bearing carriages, means for 15 sliding said supporting carriages horizontally and means for moving said bearing carriages along said inclined planes, said means cooperating to vary the relative position of the rolls.

5. In an apparatus for manufacturing transparent sheet material, in combination, a coating roll, means for supplying said coating roll with film forming material, a reverse coating roll in superimposed relation to said coating roll, a resilient roll, a carrier belt trained around said resilient roll, means for moving said resilient roll to contact the belt therearound with the coating roll at a point after the coating roll has advanced under the reverse roll, means for moving the coating roll in a horizontal plane and 30 means for moving the reverse roll along an inclined plane whereby the distance of travel of the film on the coating roll before advancing under the reverse roll and the space between said rolls can be readily adjusted.

35 6. A film forming apparatus comprising, in combination, a trough, a fountain roll rotatable through said trough, a reverse coating roll above said trough in adjustable spaced relation from the periphery of the fountain roll, a resilient roller 40 above said fountain roll, a casting belt trained around said resilient roller in contact with said fountain roll, means for rotating said fountain roll and means for rotating said resilient roller to advance the casting belt in a direction opposite to the direction in which the surface of the fountain roll is rotated.

7. A film forming mechanism comprising, in combination, a trough for containing a film forming solution, a fountain roll rotatable 50 through said trough for picking up a film of said solution on its periphery, a reverse coating roll in adjustable spaced relation from the periphery of said roller to gauge the thickness of the film thereon, a casting belt adapted to pick up the gauged film on said fountain roll and means for advancing said belt in a surface direction opposite to the direction in which the periphery of the fountain roll is rotating so that the film thereon is wiped off by the belt.

8. The process of making transparent sheet material which comprises picking up a film of sheet forming solution on a smooth rotating surface, wiping said film against a reverse rotating surface to uniformly gauge the film, contacting 65 the gauged film with a carrier belt advancing in a direction opposite to the direction in which the film is traveling to wipe the film from the rotating surface onto the belt, allowing the film to dry on the belt and stripping the resulting 70 sheet from the belt.

EDOUARD M. KRATZ.
